(57) **CLAIM**

An ornamental design for a display screen with graphical user interface, as shown and described.

DESCRIPTION

FIG. 1 is a front view of a display screen with graphical user interface displayed on an electronic device that presents an unclaimed map and a set of clustered, non-uniform circles displayed thereon; and,

FIG. 2 is a front view of another embodiment of the display screen with graphical user interface displayed on the electronic device that presents an unclaimed map with another embodiment of a set of clustered, non-uniform circles displayed thereon.

The outermost broken line showing of the display screen is for the purpose of illustrating environment and forms no part of the claimed design. The broken line showing of elements on the display screen illustrate portions of the article and form no part of the claimed design.

1 Claim, 1 Drawing Sheet
